UNITED STATES PATENT OFFICE.

HARRY A. SANGREN, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

DESIGN FOR A BRIDGE FOR AN OPHTHALMIC MOUNTING.

Application filed March 18, 1929. Serial No. 30,504. Term of patent 14 years.

To all whom it may concern:

Be it known that I, HARRY A. SANGREN, a citizen of the United States, residing at Southbridge, in the county of Worcester and State of Massachusetts, have invented a new, original, and ornamental Design for a Bridge for an Ophthalmic Mounting, of which the following is a specification, reference being made to the accompanying drawings, forming a part thereof.

Fig. 1 is a front elevation of a bridge for an ophthalmic mounting showing my new design;

Fig. 2 is a plan view of same.

I claim:

The ornamental design for a bridge for an ophthalmic mounting as shown.

In testimony whereof, I affix my signature.

HARRY A. SANGREN.
